UNITED STATES PATENT OFFICE.

WILLIAM E. WHITE, OF CHICAGO, ILLINOIS.

COLLAPSIBLE CHAIR.

Application filed February 9, 1923. Serial No. 617,949.

To all whom it may concern:

Be it known that I, WILLIAM E. WHITE, a citizen of the United States, and a resident of Chicago, in the county of Cook and State 5 of Illinois, have invented certain new and useful Improvements in a Collapsible Chair, of which the following is a specification.

My invention relates to concrete reinforcing accessories and particularly to a novel 10 chair having the function of collapsibility.

One of the principal objects of this invention is to provide means for supporting concrete reinforcing devices, such means being economically constructed and adapted 15 to be collapsed in order that the devices may occupy a minimum space in shipping. This invention is an improvement in that disclosed in my copending application, Serial No. 578,575, filed July 31, 20 1922.

The invention will be more readily understood by reference to the accompanying drawing, in which:

Figure 1 is a side elevation of a pair of 25 supporting devices constructed in accordance with my invention;

Figure 2 is an end view thereof;

Figure 3 is a perspective view;

Figure 4 is a side view somewhat enlarged 30 showing the article in its collapsed position;

Figure 5 is an end view of a slightly modified form;

Figure 6 is a side view thereof; and

Figure 7 is a similar view somewhat enlarged 35 showing the device in collapsed position.

In Figure 1 the device is illustrated in position, a pipe 10 being supported thereon, it being understood that a plurality of the 40 devices are employed in suitable spaced relation. The chair of my invention comprises two U-shaped members each having legs 11 and a horizontal portion which is vertically downwardly offset at an intermediate 45 point thereby providing a depressed horizontal portion 12 and sides 13. The sides are joined to the legs by a bend 14. The space defined by the portions 12, 13, constitutes a seat for a bar or pipe. In order to 50 form a stable structure a pair of U-shaped members such as described are employed and the legs of each member are bent at a point substantially in line with the longitudinal axis of the depressed horizontal portion 12. 55 When two of such members are assembled in opposed relation—that is with their legs

in diverging relation—a rigid structure results, dependent of course upon the joining of the contacting portions of the two members.

In order to effect the desired economy of shipping space I join the two members in order to effect collapsibility. To that end I provide a band 15 which is bent upwardly around the depressed horizontal portions 12 60 which lie, side by side, in parallelism with their longitudinal axes in the same horizontal plane. Thus the portions 13, 14, together with the upper ends of the legs 11 act as complementary stops and prevent undesired 65 lateral spread of the legs. The extent of the spread is determined by the angle of bend of the legs at the point indicated.

The depth of the seat is a matter of choice. If for manufacturing reasons, a seat of less 70 depth than that indicated in Figures 1 to 3 is desired, I may provide a collateral bar holding device such as shown in Figures 5 to 7 inclusive. In that construction the chair is identical with that just described 75 except as to the depth of the vertically depressed portion but I utilize a U-shaped member of flat material having legs 16 and an intermediate portion 17, which portion is clamped by means of the band 18 in 80 proper position with the legs extending upwardly. Preferably the material of which the U-shaped member is composed is easily 85 bendable and after a bar, indicated at 19 in Figure 5, is in position the legs 16 may 90 be bent over the bar by means of a hammer or other suitable tool.

The fundamental object in the constructions described is that of simplicity and economy in shipping space. These together 95 with rigidity in use and vertical strength under load adapts the device for general use wherever a relatively high chair is required.

The construction is capable of rather extensive modification and I do not wish to be 100 limited except as indicated in the appended claims.

I claim:

1. In a chair, the combination of a pair of U-shaped members providing four diverging 105 legs, the intermediate portion of each U-shaped member being vertically depressed to provide a seat, and means for pivotally joining the horizontal depressed portions of the two members, the portions of said members above the pivot being angularly disposed relative to said legs and acting as

complementary stops to limit the lateral separation of the legs.

2. In a chair, the combination of a pair of U-shaped members providing four diverging legs, the intermediate portion of each U-shaped member being vertically depressed to provide a seat, the plane of said depressed portion and of the portions of said legs above the depressed portion being disposed at an obtuse angle to the plane of the legs which form a part of said member, and means for pivotally joining the parallel adjacent horizontal depressed portions.

3. In a chair, the combination of a pair of U-shaped members providing four diverging legs, the intermediate portion of each U-shaped member being vertically depressed to provide a horizontal portion below the upper extremity of the member, and a band for joining the horizontal portions of said members, the portions above said pivot acting as complementary stops to limit the lateral spread of the legs.

4. In a device of the class described, the combination of a pair of wires bent into U-shape providing four laterally diverging legs, the intermediate portion of each

U-shaped member being vertically downwardly offset at a point between its ends, and a band for uniting the parallel horizontal parts of said offset portions, the portions of said members above said horizontal portions acting as complementary stops to limit the lateral separation of the legs of the respective U-shaped members.

5. In a chair, the combination of a pair of U-shaped members, the horizontal portion of each U-shaped member being vertically downwardly deflected at an intermediate point to provide a seat, the portions of said members which constitute the legs being bent at a point substantially in line with the bottom of said seat whereby when said members are assembled the upper portions are in contact and the legs of the respective members diverge from the point of bend of the legs, and means for pivotally joining the bottom portions of the offset material whereby said legs may be permitted to swing into parallelism.

Signed at Chicago, Illinois, this 7th day of February, 1923.

WILLIAM E. WHITE.
